UNITED STATES PATENT OFFICE.

ARTHUR J. WAITE, OF BINGHAMTON, NEW YORK, ASSIGNOR TO UNITED SHOE MACHINERY COMPANY, OF PATERSON, NEW JERSEY, A CORPORATION OF NEW JERSEY.

METHOD OF MAKING SHOES.

1,215,440.

Specification of Letters Patent. Patented Feb. 13, 1917.

Application filed July 14, 1916. Serial No. 108,308.

To all whom it may concern:

Be it known that I, ARTHUR J. WAITE, a citizen of the United States, residing at Binghamton, in the county of Broome and State of New York, have invented certain Improvements in Methods of Making Shoes, of which the following description, in connection with the accompanying drawings, is a specification, like reference characters 10 on the drawings indicating like parts in the several figures.

This invention relates to improvements in methods of making shoes and particularly 15 stitch-down shoes which have the margin of the upper turned outwardly to form an attaching flange which lies over and is sewed to the top face of the margin of the sole. Care has to be exercised in making this type 20 of shoe to shape the upper into an angular formation between the outturned flange and the body portion of the upper in order to make the shoe fit the foot and to obtain a pleasing appearance particularly around the toe and the heel ends of the shoe. Molding 25 of the upper materials, including the toe and heel stiffeners, has been practised as described in United States Letters Patent Nos. 998,682 and 1,001,745, granted on applications of Karl Engel, July 25, 1911 and Aug. 30, 1911, respectively, but is expensive and many stitch-down shoes are now made by wetting the upper materials, including a strip of heel stiffening material, to render 35 them pliable, assembling them with a marginally projecting innersole upon a last, and stapling through the upper materials and innersole as close as possible to the side of the last, and then allowing the said upper materials to dry in their acquired shape as 40 described in United States Letters Patent Nos. 1,117,086 and 1,117,087, granted on applications of A. H. Prenzel, Nov. 10, 1914. This is a rapid system having a low labor cost and producing a marketable play shoe. 45 An object of this invention is to improve upon this and similar procedures so as to approximate the better shape obtained from toe and heel molding. In one of its aspects the invention consists in assembling an upper 50 and a stiffener previously molded to fit the outer face of the heel part of a last and to present an outturned flange and using the stiffener as a form to which to shape the heel portion of the upper to produce an outturned sole attaching flange thereon and a

welt crease, and securing the upper in said shaped relation to the stiffener flange. This method has the advantage that the stiffener can be produced, as an article of manufacture, by the use of known machinery, with 60 any degree of perfection of shape adapting it to serve as a form over which to mold the upper, and then can be assembled with an upper, as for example between the upper and its lining and on a last with or without a sole or innersole. The relatively pliable upper, with or without moistening, can then be shaped to the form of the stiffener to fit into the angle between the body and the outturned flange of the stiffener and to present 70 an outturned flange. The upper may be secured in its shaped relation to the molded stiffener, as for example by staples driven through the upper and stiffener flanges and the inner sole, if one is present, and located 75 in the angle with their bars extending lengthwise of the flange. It is customary to complete the shoe by applying a welt in the angle or welt crease and stitching the sole on through the welt, the flanges and the projecting margin of the innersole and sole, and a welt so applied permanently binds the upper in molded relation to the stiffener in the angle or crease.

The invention will now be more fully explained in connection with the accompanying drawings and will then be pointed out in the claims.

Figure 1 of the drawings shows an upper for a stitch-down shoe and a stiffener molded to conform to the shape of an end portion of a last and present an outturned flange.

Fig. 2 shows the upper and stiffener assembled on a last which is provided with an innersole.

Fig. 3 shows the upper being molded to the shape of the body and flange of the stiffener and into the angle thereof to produce a welt crease, and shows the upper being fastened in molded relation to the stiffener by a staple.

Fig. 4 shows a portion of a completed shoe made by the practice of this invention.

The shoe upper is shown as indicated at 2 and the lining at 4 while 5 indicates a molded heel stiffener comprising a body portion shaped like the side faces of the heel portion of a last, and a flange 6 turned outwardly from the lower edge of the body and 110

forming therewith an acute angle. A last is indicated at 8 in Fig. 2 and has an inner-sole secured to its tread face by tacks that are later to be pulled out. A tool 10 may 5 conveniently be used to assist in conforming the upper to the shape of the molded stiffener and fastening the upper in that shape.

In practising the invention the stiffener is molded to give it the characteristics referred 10 to and adapt it to be used as a form upon or over which to shape the upper as to vertical contour, the lengthwise contour of the upper being determined by the last upon which the stiffener and upper are preferably assembled 15 as in Fig. 2. In the procedure illustrated in the drawings, the upper is pressed into the angle of the stiffener and shaped to the adjacent body and flange faces, as shown in Fig. 3, by a suitable tool that may be considered as complementary to the stiffener in shaping or molding the upper. When this tool is used it is applied progressively around the end of the shoe. The shaping might be performed by embracing the entire 25 end portion of the shoe at one time, and it will be understood that the invention is not limited in this respect. It may be here noted that the invention is herein described particularly with reference to the heel end 30 of the shoe, its application to the toe end being readily understood from this explanation.

Sufficient permanence of the shape given to the upper in conformation to the contour 35 of the heel stiffener may be obtained in various ways, as for example by pressure of sufficient degree or applied through a sufficient time to prevent undesirable reaction or by the use of adhesive, or fasteners. I 40 prefer to employ staples arranged with their bars extending lengthwise of the welt crease and driven in the angle through the upper and the stiffener flange. Suitable staples 9 can advantageously be driven through the 45 forming tool 10 by known driving mechanism and clenched on a table 12. The permanence of shape of the upper in conformat- 50 ing to the molded stiffener may be further insured by the application of a binder, here- 55 in shown as a welt 14 attached by a sole attaching seam 15. A binder may under some conditions be used without stapling.

Having explained the nature of the invention and described how it may be practised, I claim as new and desire to secure by Letters Patent of the United States:—

1. That improvement in methods of making shoes which comprises assembling on a last an upper and a molded heel stiffener 60 having an outturned flange; and shaping the

upper to produce a sole attaching flange for the rear part of a stitch-down shoe by forming the upper into the angle between the body and the flange of the stiffener and fastening it with the margin of the upper 65 turned outwardly over the flange of the stiffener.

2. That improvement in methods of making stitch-down shoes which comprises assembling an innersole, an upper and a 70 molded stiffener having an outturned flange; shaping the upper by forming it into the crease between the flange and the body of the stiffener; and inserting through the upper, stiffener and innersole, staples located 75 in said crease and having their bars extending lengthwise of the crease.

3. That improvement in methods of making shoes which comprises assembling a molded heel stiffener having an outturned 80 flange between an upper and a lining, using the outer face and the outturned flange of the stiffener as a form over which to shape the upper, and securing the upper in shaped relation in the angle between the flange and 85 said face of the stiffener.

4. That improvement in methods of making shoes which comprises assembling a molded heel stiffener having an outturned flange between an upper and a lining, using 90 the outer face and the outturned flange of the stiffener as a form over which to shape the upper, and stitching a welt in position to hold the margin of the upper snugly in the angle between the flange and said face 95 of the stiffener.

5. That improvement in methods of making shoes which comprises assembling a molded heel stiffener having an outturned flange and an upper together and using the 100 stiffener as a form to which to shape the heel portion of the upper to produce an outturned flange and a welt crease, and confining the upper in such shaped relation to the stiffener.

6. That improvement in methods of making shoes which comprises molding a stiffener to conform to the shape of an end portion of a last and present an outturned sole attaching flange, assembling said stiffener 110 with a relatively pliable upper, using the stiffener as a form to which to shape the upper to present an outturned sole attaching flange overlying the flange of the stiffener and a welt crease lying in the angle between the body and the flange of the stiffener, and confining the upper in said angle.

In testimony whereof I have signed my name to this specification.

ARTHUR J. WAITE.
